(57) **CLAIM**

The ornamental design for a vehicle hood insert, as shown and described.

DESCRIPTION

FIG. 1 is a perspective view of the vehicle hood insert; FIG. 2 is a front view thereof; FIG. 3 is a top view thereof; and, FIG. 4 is a left side view thereof (where the right side view is a mirror image thereof). The broken lines in the drawings illustrate portions of the vehicle hood insert that form no part of the claimed design.
